Des. 191,912
Patented Dec. 12, 1961

191,912

GOLF CLUB COVER

Richard A. Arms, 1360 Hillview Drive, Menlo Park, Calif.

Filed July 17, 1961, Ser. No. 65,955

Term of patent 14 years

(Cl. D34—5)

FIG.4

FIG.1

FIG.2

FIG.3

I claim:

The ornamental design for a golf club cover, as shown.
